UNITED STATES PATENT OFFICE.

LANE JOHNSON, OF INGRAM, PENNSYLVANIA.

COT.

1,427,476.

Specification of Letters Patent. Patented Aug. 29, 1922.

Application filed February 1, 1921. Serial No. 441,549.

To all whom it may concern:

Be it known that I, LANE JOHNSON, a citizen of the United States, and a resident of Ingram, in the county of Allegheny and State of Pennsylvania, have invented a new and useful Improvement in Cots, of which the following is a specification.

The object of this invention is to provide a collapsible cot, particularly for outdoor use, which is light in weight, simple in construction, and which may be readily set up and taken down, and when taken down may be rolled or folded into compact and easily transportable form.

15 The invention is illustrated in the accompanying drawings of which Fig. 1 is a plan view of the cot when set up; Fig. 2 a longitudinal vertical sectional view; Fig. 3 a transverse sectional view taken on the 20 line III—III, Fig. 1; and Fig. 4 a plan view of the left end of the cot showing a modification of construction.

The cot comprises two frames, each of which includes a horizontal strut and vertical legs attached to its outer ends, and a supporting fabric arranged between and connected to the struts. Projecting downwardly and outwardly from each strut, there is an anchoring member, the outer portion 30 of which is adapted to be fastened to the ground, and one or both of the anchoring members are adjustable so that the fabric between the struts may be spread taut to properly support the person lying on the 35 cot.

Having reference to the embodiment of the invention illustrated in the drawings, each end frame may consist of a horizontal strut 1 which may be made of wood or other 40 suitable rigid and light material, and vertical legs 2 which are preferably pivotally connected to the outer ends of the strut. The pivotal attachment of the legs to the strut is preferably such that the legs may swing 45 only through an arc of substantially ninety degrees from positions adjacent to the strut to positions substantially at right angles thereto. For this purpose, hinges 3 may be attached to each strut and its legs in the 50 manner particularly shown in Fig. 3, the arrangement being such that the legs 2 may move from their full line positions to those indicated in dotted lines, but may not move outwardly beyond their full line positions.

The fabric 4 arranged between the struts 55 may be canvas such as is ordinarily used in collapsible cots, although other suitable flexible materials may be used. The fabric preferably extends over the top of each strut and may be connected to the struts by 60 strips 5 sewed to the under side of the fabric and forming with the fabric pockets for receiving the struts. If desired a flap 7 may be attached to the fabric 4 adjacent to one or both of the struts for the purpose of pinning the foot end of a blanket to the cot. The ends of the fabric preferably project beyond the struts to form or to be attached to anchors. The projecting end 6 is indicated as being longer than the other projecting end and is provided at its outer edge with openings to receive anchoring pins or stakes 8 adapted to be driven into the ground in sufficient numbers to adequately anchor the full width of the end. For forming 70 an adjustable anchor at the other end of the cot, the projecting fabric end 9 may, as shown particularly in Fig. 1, be attached to an anchoring strip of fabric 10 by means of a lacing 11, the strip 10 being provided 75 with openings to receive anchoring pins 12, and such strip and the fabric end 9 being provided with eyelets 13 for the lacing 11. As an example of other forms of anchors that may be used in place of the fabric 80 strips, Fig. 4 shows springs 15 provided at their opposite ends with rings to receive the lacing and stakes.

To set up the cot, it may be laid on the ground and pins or stakes passed through 90 the openings or pin holes of the end anchors, or through the outer rings of the springs, and driven into the ground. The struts 1 may then be raised and the legs 2 turned downwardly to support them. Thereafter, 95 the lacing 11 may be tightened to spread the fabric 4 sufficiently taut to support a person. Because the lower ends of the legs 2 are supported on ground at least sufficiently soft to permit the driving of the anchoring pins, 100 such legs may not be readily turned inwardly, nor may they be otherwise slid along the surface of the ground to cause the cot to collapse. If, due to different humidity conditions, the fabric 4 stretches or shrinks, 105 compensation may be readily made for this by adjusting the lacing 11.

To take the cot down, it is only necessary

to release the lacing and withdraw the pins from the end anchors. The legs 2 may then be folded upon the struts 1 to the dotted line positions shown in Fig. 3, and the entire 5 cot rolled into a small space and inserted in a casing 14 shown on top of the cot. The casing is of such form that a person's clothes may be readily placed in it and then used for a pillow, as indicated in the drawings.

10 While unlimited to any specific use or uses, the cot is particularly suitable for camping purposes and to be carried in automobiles on touring journeys. It is very light in weight and may be folded into quite compact form 15 and is thus rendered convenient and suitable for the particular purposes mentioned.

According to the provisions of the patent statutes, I have described the principle and operation of my invention together with the 20 cot which I now consider to represent the best embodiment thereof. However, I desire to have it understood that, within the scope of the appended claims, the invention may be practiced with other forms of construction than that specifically shown and described herein.

I claim:

1. A collapsible folding cot comprising when set up two end frames each including 30 a horizontal strut and legs pivotally connected to its outer ends, a supporting fabric arranged between and connected to said struts and having end portions projecting beyond the struts, one of said ends being provided 35 with openings at and intermediate of its ends to receive anchoring pins, and an anchor provided with pin openings at and intermediate of its ends adjustably connected to the other of said cot ends whereby the fabric 40 may be spread and held taut after the cot is

set up and pins extending through the pin openings driven into the ground.

2. A collapsible folding cot comprising when set up two end frames each including a horizontal strut and vertical legs connected 45 to its outer ends, a supporting fabric arranged between and connected to said struts and having end portions projecting beyond the strut, an anchoring strip provided with openings at and intermediate of its ends to 50 receive pins, a lacing between said projecting fabric and said strip, and an anchoring member attached to the other end of said fabric provided with pin openings at and intermediate of its ends.

3. A collapsible folding cot comprising when set up two end frames each including a horizontal strut and legs pivotally connected to its outer ends to swing only through an arc of substantially ninety degrees from 60 positions adjacent to the strut to positions substantially at right angles thereto, and a supporting fabric arranged between and connected to said struts and having end portions projecting beyond the struts, one of said ends 65 being longer than the other and being provided with openings at and intermediate of its ends to receive anchoring pins, and an anchor adjustably connected to the other of said fabric ends, said adjustably connected 70 anchor comprising a strip provided with openings at and intermediate of its ends to receive pins and a lacing between the strip and said smaller projecting end of the fabric.

In testimony whereof, I have hereunto set 75 my hand.

LANE JOHNSON.

Witness:

EDWIN O. JOHNS.
